QUICKLY ADJUSTABLE VISE

Filed March 19, 1945

UNITED STATES PATENT OFFICE

2,441,683

QUICKLY ADJUSTABLE VISE

Berthold R. Zitner, Milwaukee, Wis.

Application March 19, 1945, Serial No. 583,610

4 Claims. (Cl. 81—30)

1

This invention relates to improvements in quickly adjustable vises.

The conventional vise is adjusted through the turning of a screw to position the movable jaw of the vise relative to the stationary jaw thereof for clamping or releasing the work. Continuous movement of the adjustable jaw through turning movement of the operating screw is slow and tedious.

It is, therefore, a primary object of the present invention to provide a vise wherein the movable jaw of the vise may be slid into and out of rough positions of adjustment, coupled with screw fed movements for final clamping adjustments and release therefrom, whereby operation of the vise is rendered easy and expeditious.

A further object of the invention is to provide a vise arranged for screw fed movements of the movable jaw of the vise for clamping and initial release, and for fast longitudinal sliding movements of said movable jaw for rough positions thereof, together with means controlled by limited turning of the screw mechanism for changing to and from screw feed control of the movable jaw.

A further object of the invention is to provide a vise of the character described having simple and effective operating mechanism, which is strong and durable, which is inexpensive to manufacture, and which is well adapted for the purposes described.

With the above and other objects in view the invention consists of the improved vise, and its parts and combinations as set forth in the claims, and all equivalents thereof.

In the accompanying drawing in which the same reference characters indicate the same parts in all of the views:

Fig. 1 is a longitudinal vertical sectional view of the improved vise taken on line 1—1 of Fig. 2;

Fig. 2 is a plan view of the vise with parts broken away and in section; and

Fig. 3 is a transverse vertical sectional view taken on line 3—3 of Fig. 1.

Referring now more particularly to the drawings it will appear that the stationary unit of the vise is indicated generally by the numeral 5, and the movable section is indicated generally by the numeral 6. The former includes a box section 7 having a rectangularly shaped

2

opening 8 extending longitudinally therethrough below which there is a flanged flat base portion 9 formed with apertures 10 to permit the securing of the vise to a bench, table, or other support. The forward upper end of the unit 5 is curved and shaped to form a jaw 11. Fast within a recess therefor in the top surface of the base portion 9 is an elongated ratchet tooth plate 12 whose teeth project upwardly relative to the lower portion of the opening 8, and are angled rearwardly. The plane of the top surfaces of the teeth is coincident with the bottom of the opening 8 so that a member extended into said opening, and to be described hereinafter, is free to slide longitudinally.

The movable section 6 of the vise includes an elongated, rearwardly projecting, rectangularly shaped, hollow sleeve 13 which extends into and through the opening 8 of the box section 7, closely fitting the same. A portion of the bottom wall of the sleeve 13 over some of the ratchet plate teeth, is open as is shown in Fig. 1. The forward end of the section 6 has a screw threaded bore 14 therethrough, communicating with the hollow interior of the sleeve. Above said end portion of the section 6 there is an integral curved jaw forming portion 15 directed and arranged so as to be complementary to the jaw 11.

A tubular socket member 16 has its inner end slightly reduced and formed as a screw 17, the threads thereof being left hand and being engaged in the screw threaded bore 14 of the section 6. The screw portion 17 is formed with an enlarged bore 18 affording communication between the hollow interior of the socket member 16 and the interior of the hollow sleeve 13. Within the shoulder formed at the inner end of the interior of the socket member 16, there is disposed a washer 19 which engages the semi-spherical head portion 20' of an elongated tie rod 20. Compressed between the flat outer face of the semi-spherical head 20' of the tie rod 20 and another washer 21 within the socket member 16 is a coiled spring 22. The washer 21 is held against the outer end of the spring by an operating handle 23 which is inserted through openings therefor in the outer end of the socket member 6 and is passed diametrically through the socket member. A pawl or ratchet member, 50 operatively disposed within the hollow sleeve 13,

is indicated generally by the numeral 24. This pawl is formed with upwardly projecting side flanges 25 between which the rectangularly shaped inner end of the tie rod 20 is disposed, said inner end portion of the tie rod carrying a transverse pin 26 whose end portions have pivotally mounted thereon the portions 25 of the pawl 24. The lower block portion of the pawl has extending transversely therethrough, toward its forward end, a slot 27 through which a transverse pin 28 extends, the outer ends of said pin being anchored in side wall portions of the sleeve 13. The arrangement of the slot 27 and the supporting pin 28 permits of some back and forth play during the operative movements of the pawl 24. However, the disposition of said parts is normally maintained in the relationship shown in Fig. 1 due to the pressure exerted by a coiled spring 29 housed within a recess in the block portion of the pawl and bearing against the transverse pin 28. The amount of pressure exerted by the spring 29 may be varied by an adjusting screw 30 impinging against the other end of the spring. The lower, forward end of the block portion of the pawl is formed as a transverse pawl tooth 31 cooperative with selected teeth in the ratchet plate 12.

In the operation of the improved quickly adjustable vise, when the parts are in the positions shown in Fig. 1, the movable vise section 6 is free for quick sliding movement relative to the stationary unit of the vise. Consequently, by manually grasping the section 6 and by pushing it toward the vise section 5 a desired distance and into proximity to the work to be clamped between the vise jaws 11 and 15, a rough adjustment may be quickly accomplished solely by the sliding movement of the sleeve 13 within the opening 8 of the box section 7 of the stationary unit of the vise. Upon quickly attaining the sliding rough adjustment of the movable section of the vise, the work may be clamped between the vise jaws 11 and 15 through a few quick turns imparted to the socket screw unit 16-17 through the operating handle 23. When the handle is turned in a proper direction, movement of the screw 17 in the threaded bore 14 of the section 6 will serve to draw the tie rod 20 forwardly. As the pawl 24 is pivotally connected to the inner end of the tie rod 20 by the pin 26 and is furthermore rockingly and shiftably mounted on the transverse pin 28 carried by the sleeve 13, the forward movement of the tie rod 20 will cause a downward tilting of the toothed end 31 of the pawl to cause said tooth 31 of the pawl to enter a registering tooth in the ratchet plate 12. During the tilting movement of the pawl there is slight yielding sliding movement of the pawl relative to the pin 28 by virtue of the elongated slot 27. As the pawl 24 is, through the operation described, in engagement with the ratchet plate 12, further turning of the screw 17 in the same direction through manipulation of the handle 23 exerts a pull on the tie rod 20 which, because of the engagement of the pawl with the ratchet plate, is transmitted to the movable section 6 to cause said movable section to be drawn toward the stationary unit 5 to clamp the work between the vise jaws 11 and 15.

When it is desired to release or unclamp the work, it is merely necessary to turn the socket screw unit 16-17 in the opposite direction through manipulation of the handle 23. This turning movement of the unit 16-17, through compression of the spring 22 within the socket member,

forces the tie rod 20 rearwardly, whereby the pawl 24 tilts upwardly toward the position of Fig. 1 to disengage its tooth 31 from the ratchet plate 12. Thereupon, through manual engagement of the movable section 6 of the vise and quickly sliding the sleeve 13 within the box section 7, the movable section of the vise may be slid rapidly to any location or distance relative to the stationary vise unit 5 within the range of the vise 10 and to suit the convenience of the operator and the work requirements.

The improved quickly adjustable vise is simple and expeditious in operation, is strong and durable and effective, minimizes the time required in adjusting the vise for the clamping and releasing of the work, embodies simple mechanism, and is well adapted for the purposes set forth.

What is claimed as the invention is:

1. A vise, comprising a stationary jaw unit 20 formed with an open box-like section having a toothed portion, a movable jaw unit formed with a sleeve slidably engaging said box-like section, a screw turnably associated with the movable jaw unit, a pawl, means operatively mounting the pawl within said sleeve for engagement and disengagement with said toothed portion including a slot in said pawl and a pivot pin fixedly carried by said sleeve and extending through said slot, a rod associated with the screw and extending to the pawl for controlling the pawl upon certain turning movements of the screw, and a spring interposed between the rod and the screw.

2. A vise, comprising a stationary jaw unit 35 formed with an open box-like section having a toothed portion, a movable jaw unit formed with a sleeve slidably engaging said box-like section, a screw turnably associated with the movable jaw unit, a pawl, means yieldingly and operatively mounting the pawl within said sleeve for engagement and disengagement with said toothed portion including a slot in said pawl, a pivot pin fixedly carried by said sleeve and extending through said slot, a spring within the pawl and exerting pressure relative to the pawl and pin to yieldingly urge the pawl to a position wherein the pin lodges within the forward end of the pawl slot, means adjustably carried by the pawl and engaging the spring to vary the tension exerted by the spring, and means associated with the screw and extending to the pawl for controlling the pawl upon certain turning movements of the screw.

3. A vise, comprising a stationary jaw unit 55 formed with an open box-like section having a toothed portion, a movable jaw unit formed with a sleeve slidably engaging said box-like section, a screw threadably associated with the movable jaw unit, a pawl yieldingly pivotally associated with the sleeve and engageable and disengageable with the toothed portion of the box-like section, a tie-rod floatingly interposed between the screw and the pawl for controlling the pawl upon certain turning movements of the screw, and means between the screw and tie-rod for resiliently urging the tie-rod to a pawl disengaging position.

4. A vise, comprising a stationary jaw unit formed with an open box-like section having a toothed portion, a movable jaw unit formed with a sleeve slidably engaging said box-like section, there being a threaded opening through a portion of the movable jaw unit aligned with said sleeve, a hollow screw turnably mounted in said threaded opening, a pawl, means yieldingly pivotally mounting the pawl within said sleeve for engagement and disengagement with said toothed por-

5

tion, a tie rod extending loosely through said hollow screw and pivotally connected to said pawl, and a spring confined within a portion of said screw and exerting pressure against an end of said tie rod.
